UNITED STATES PATENT OFFICE.

ARTHUR V. EGINTON, OF MERIDEN, CONNECTICUT, ASSIGNOR TO INTERNATIONAL SILVER COMPANY, OF MERIDEN, CONNECTICUT, A CORPORATION OF NEW JERSEY.

DESIGN FOR A CASKET NAME-PLATE.

No. 37,679.

Specification for Design.

Patented Nov. 14, 1905.

Application filed September 11, 1905. Serial No. 278,050. Term of patent 7 years.

To all whom it may concern:

Be it known that I, ARTHUR V. EGINTON, a citizen of the United States, residing at Meriden, in the county of New Haven and State of Connecticut, have invented a new, original, and ornamental Design for a Casket Name-Plate; and I do hereby declare the accompanying drawing to be a full, clear, and exact illustration of the same, and which said drawing constitutes part of this specification, and rep-

resents a face view of a casket name-plate embodying my design.

I claim—

The ornamental design for a casket name-plate as shown.

ARTHUR V. EGINTON.
